HYDROCARBON BURNER

George Pirich, Minneapolis, Minn.

Application June 12, 1937, Serial No. 147,877

6 Claims. (Cl. 158—53)

My present invention relates to hydrocarbon burners, more commonly designated as oil burners and provides highly important contributions to this art.

5 Hydrocarbon burners may be broadly divided into two general classifications, to wit: (a) the so-called gun type burners, wherein low grades of hydrocarbon fuel such as fuel oil are mechanically broken up into fine particles and sprayed 10 into the combustion chamber in a mist-like state and burned in that condition, and without previous application of heat; and (b) the so-called generating or vaporizing type of burner, wherein the hydrocarbon fuel is heated to a point above 15 its critical temperature by the process known as generation and is delivered to the combustion chamber in a volatile or gasified condition and burned as a gas. This invention relates to this latter type of burner, designated as (b) above.

20 Burners of this generating or vaporizing type, designated as (b) above, have long been regarded as the most efficient type for use with low grade hydrocarbon fuels, but, since hitherto produced burners of this type have been difficult to 25 ignite, particularly when cold, this type of burner has largely been displaced by the less efficient but, nevertheless, more easily ignited so-called gun type, designated as (a) above, since in this gun type, ignition is comparatively easy and can readily be accomplished by conventional automatic ignition systems.

One very important object of the invention is the provision of a highly efficient hydrocarbon burner of the so-called generating or vaporizing 30 type, wherein low grade hydrocarbon fuel such as fuel oil is prepared for combustion and can easily be ignited, even when the burner is in a cold state, and wherein the hydrocarbon fuel will be subject to the process of self-generation or 35 vaporization after combustion is established, to thereby materially raise the efficiency of the burner.

Another equally important object of the invention is the provision of an improved ignition system 40 for hydrocarbon burners, which ignition system, while adapted for use in connection with various different types of hydrocarbon burners, is particularly used in connection with hydrocarbon burners of the generating or vaporizing 45 type and is herein illustrated in connection with my improved generating type burner.

The above and numerous other important objects and advantages of the invention will be made apparent from the specification, claims 50 and drawings. In the accompanying drawings

like characters indicate like parts throughout the several views.

Referring to the drawings:

Fig. 1 is a view in side elevation of one of two forms of my invention herein illustrated and 5 described;

Fig. 2 is an enlarged detail view taken on the line 2—2 of Fig. 1;

Fig. 3 is an enlarged detail view sectioned on the line 3—3 of Fig. 2, looking downwardly and 10 turned 90° in a clockwise direction;

Fig. 4 is a sectional view taken on the line 4—4 of Fig. 3;

Fig. 5 is a view in side elevation, with some parts broken away and some parts shown in section, of another form of burner made in accordance with the instant invention;

Fig. 6 is an enlarged detail view taken on the line 6—6 of Fig. 5;

Fig. 7 is a detail sectional view taken on the 20 line 7—7 of Fig. 6 and turned 90° in a clockwise direction;

Fig. 8 is a sectional view taken on the line 8—8 of Fig. 7; and

Fig. 9 is a sectional view taken on the line 25 9—9 of Fig. 7.

With reference first to the form of the invention illustrated in Figs. 1 to 4, inclusive, the numeral 10 indicates a motor driven blower having an eye inlet opening 11, a vane-equipped rotor 12, a rotor shaft 13, and a tangential discharge barrel 14. The blower 10 is mounted on a suitable base of support 15, also mounted on which base of support is a fluid pressure pump 16 that is driven from the motor driven blower shaft 13 through driving connections comprising belts and pulleys 17. The fluid pressure pump 16 may be assumed to have its inlet connected to a suitable source, not shown, of hydrocarbon fuel such as fuel oil, by a fuel conduit 18. The outlet of the pump 16 is connected by a pipe 19 to a fuel discharge nozzle 20 located within the discharge end of the blower discharge barrel 14. The parts thus far described constitute the major elements of a so-called gun type of burner, 45 in which fuel projected from the nozzle 20 under relatively high pressure created by the pump 16 is mixed with the air passing through the discharge barrel 14 of the blower and burned off the end of the nozzle 20 in a mechanically broken-up cold state.

In accordance with the forms of my invention herein chosen for the purpose of illustration, a generating type burner head, indicated as an 50 entirety by 21, is mounted on the open end of 55

the discharge end of the barrel 14 of the blower, so that air and oil emanating from the discharge barrel 14 and nozzle 20 mix within and pass through this burner. This nozzle burner head, 5 which in a generic sense forms a continuation of the discharge barrel 14 is preferably formed of cast iron and is provided at its intake end with a sleeve-like mounting flange 22 that is telescoped over the discharge end of the barrel 14 and de- 10 tachably secured thereto by screws or the like 23. Immediately outwardly of the coupling sleeve 22 the cast head 21 is formed to afford a primary fuel and air mixing chamber 24 that opens into branch generating or vaporizing ducts 25 that 15 diverge outwardly from the primary mixing chamber 24 and discharge into a common combustion chamber 26. These tortuous branch generating ducts 25 preferably open somewhat tangentially to the vertical axis of the combustion 20 chamber 26, so that the fuel and air mixture entering the combustion chamber 26 from opposite generating ducts or tubes 25 will set up more or less of a vortex within the combustion chamber 26. The combustion chamber 26, in this 25 form of the invention, is in the form of an open topped pot that extends a greater distance below the branch generating ducts 25 than above the same and is provided in its walls below the generating ducts 25 with numerous flame dis- 30 charge orifices 27.

At this point it may be well to state that liquid fuel injected into the air stream in the mixing chamber 24 by the nozzle 20 mixes with the air and passes through the generating conduits or 35 ducts 25 and is delivered into the fire pot in the nature of a cold mist, which may be ignited by suitable means, and burns in the fire-pot-like combustion chamber 26. This cold mixture of oil and air is readily ignitable in the combustion 40 chamber, even in the absence of any pre-heating whatever, but when ignition occurs, a relatively large flame will issue from the open upper end of the combustion chamber 26; and smaller flames will issue from the numerous orifices 27 in the 45 lower portion of the combustion chamber below the plane of the generating ducts 25. These smaller flames will very rapidly heat up the entire burner-head structure, inclusive of the tortuous generating or vaporizing ducts 25; and 50 when these are heated, combustion will be much more complete than when the structure is cold, and the efficiency of the burner will be materially increased. In other words, when the walls of the tortuous passages become hot, the cold fuel 55 particles will be heated beyond their critical temperature and will be vaporized and mixed with the air in a vaporized condition, thereby producing a more highly combustible mixture than is the original cold mixture. The lighter particles 60 of oil issued from the nozzle 20 will, for the most part, be carried by the air stream directly through the tortuous passages without being impinged upon or brought into surface contact with the walls of the ducts 25, but the heavier and harder- 65 to-burn particles, along with some of the smaller particles, will be impinged against the tortuous walls of the generating ducts 25, where they will immediately be vaporized and returned to the air stream as a vapor. Of course, when starting 70 cold, those oil particles which are impinged upon the surfaces of the passages will tend to condense on those surfaces, but, as previously stated, the surfaces are brought up to a high temperature very rapidly after combustion is established, so 75 that any moisture collected on these surfaces

during the initial warming up period will be completely vaporized and returned to the air stream and later burned.

Preferably the burner head will be sloped slightly toward the combustion chamber 26, so that such fuel as condenses upon the cold surfaces of the generating passages 25 during the initial warming up period will tend to flow toward and into the combustion chamber 26.

The burner described incorporates a novel ignition system immediately to be described. Above the primary mixing chamber 24 the burner head 21 is provided with a small auxiliary combustion chamber 28. The rear end of this small auxiliary combustion chamber 28 opens into the blower discharge barrel 14 through a port 29, see Figs. 2 and 4, and the front end of this small auxiliary combustion chamber 28 is connected by a fire flue 29' to the interior of the burner combustion chamber 26. Leading into the small auxiliary combustion chamber 28 from the primary mixing chamber 24 is a fuel mixture diverting passage 30. This passage 30 is afforded by a relatively small tube 31 that has its lower rear end located to intercept part of the sprayed fuel and air mixture moving through the primary mixing chamber 24. Fuel and air mixture thus intercepted by the tube 31 is delivered diagonally into the small secondary combustion chamber 28 and mixed with the air stream which passes through the secondary combustion chamber 28 and fire flue 29' under pressure produced in the barrel by the blower.

For establishing primary ignition I provide a pair of spaced sparking electrodes 32, the ends of which terminate just short of the path of travel of sprayed fluid passing through the tube 31. These electrodes 32, which are conventional in character, and may be assumed to be energized from a suitable high voltage source, may be supported in any desired manner, but, as illustrated, this is accomplished through the medium of insulating tubes 33 and brackets 34 from the oil delivery tube 19. The sides and bottom of the secondary combustion chamber 28 and fire flue 45 29' are formed in the cast burner head, but the top wall of said flue and secondary combustion chamber are formed by a detachable cover 35, which, when removed, permits access to the electrodes 32 and tube 31.

To start the burner the motor driven blower 10 and motor driven pump 16 are simultaneously set into motion, and simultaneously therewith the electrodes 32 are energized so as to produce a high tension arc between the free ends of the electrodes. Under the action of the blower air will be moved through the various passages in communication with the blower barrel 14 at quite high velocity, and under the action of the pump 16 a relatively high fluid pressure will be built up in the oil delivery pipe 19, with the result that oil will be broken up into fine particles by the nozzle 20 and projected into the primary mixing chamber 24 in the nature of a fine spray which will, as previously pointed out, for the most part, be carried through the tortuous ducts 25 with the air with which it will be mixed and delivered to the combustion chamber 26 in the form of a cold but, nevertheless, combustible mixture. Part of the oil and air mixture moving in the primary mixing chamber 24 will be diverted to the auxiliary combustion chamber 28, where it will immediately be ignited by sparking between the electrodes 32; and as soon as the ignition takes place within the auxiliary or secondary

5 combustion chamber 28, the flame will be blown through the fire flue 29a' into the main combustion chamber 26, where it will immediately ignite the cold fuel and air mixture issuing from the generating ducts 25. As a matter of fact, in operation ignition will be established in the auxiliary combustion chamber 28, and the resultant flame will be delivered to the main combustion chamber 26 almost simultaneously with 10 the initial delivery to the combustion chamber 26 of combustible mixture through the generating passages 25.

15 The arcing ends of the electrodes 23 do not need to be extended into the fuel spray issuing from the upper end of the diverging tube 31 but may be terminated in rearwardly spaced relation thereto, since the air stream moving in the direction of the issuing mixture will blow the sparks or arcs into the mixture to ignite 20 the same. This is, in fact, in accordance with conventional practice, in connection with the so-called gun type of burner. Of course, another function of the ignition system described is further pre-heating of the burner head.

25 This type of burner and the ignition system herein disclosed and described has been thoroughly tried out and has proved highly satisfactory. In practice it has been found that combustion is almost instantaneous when starting 30 with a cold burner head, but that the characteristics of the flame improve very greatly under heating of the burner head during the first minute or two of operation. In practice, substantially, the entire burner head 21 will be projected into the fire box and boiler or furnace, and in Fig. 3 one wall of such a fire box wall is indicated by x.

35 The modified form of burner shown in Figs. 5 to 9 inclusive will next be described. This modified type of burner is very similar to the burner described in connection with Figs. 1 to 4 inclusive and differs from the first described burner mainly in the fact that its main combustion chamber is horizontally disposed in place of being 40 vertically disposed as in the first example. Due to the similarity between the structures, parts in the latter structure which are like those in the first will not be described but will merely be designated by numerals corresponding to those 45 assigned to like parts described in Figs. 1 to 4, plus the exponent a.

50 The horizontally disposed combustion chamber of the form of burner shown in Figs. 5 to 9 inclusive is indicated by the numeral 40 and is formed by a horizontally disposed cup 41, the sides of which are illustrated as being imperforate. In this form of the invention pre-heating of the burner head is brought about through the use of an annular flame-intercepting and direction-reversing baffle 42, which is formed of suitable heat resisting material such, for example, as fire clay. This baffle 42 surrounds the major portion of the combustion chamber 40 and has its front end turned inwardly about the free end of the 55 fire chamber forming cup 40 but in spaced relation to the latter to provide a reversely curved flame diverting passage 43. By reference particularly to Figs. 7 and 8 it will be seen that the baffle 42 is provided with an axial opening 44 60 that is concentrically disposed with respect to the combustion chamber 40 but is of somewhat less diameter than that of the combustion chamber 40.

65 In this form of the invention, as in the previously described form, the major portion of the

burner head 21a can be extended into the fire box and furnace boiler or the like, but in this form the flame will issue in a horizontal direction from the combustion chamber 40 and part of this flame will be backwardly or rearwardly diverted about the intermediate portion of the burner head 21, inclusive of the generating ducts or passages 25a thereon, by the annular baffle 42. In Fig. 5 this latter type of burner is illustrated as being installed in the conventional type of 10 boiler, indicated as an entirety by 45, and which boiler has at its base portion a fire box 46. The walls of the fire box 46 are preferably formed in the conventional manner by refractory substance such as fire brick 47. The burner head 15 21a projects horizontally into this fire box 46 through the refractory walls 47 thereof, which latter serves to support the burner head. The deflecting baffle 42 may be supported in concentric but spaced relation to the combustion 20 chamber forming cup 41 in any desired manner such, for example, as by a refractory wall 48 located in the intermediate portion of the fire box 46.

25 In Fig. 5 this wall 48 is illustrated as being one 30 wall of an auxiliary fire box 49 that is approximately centrally disposed within the fire box 46 but has its walls spaced from the walls of the fire box 46 to afford flame passages 50 between the walls of the fire box 46 and the walls of the auxiliary fire box 49. The walls of the auxiliary fire box 49 are perforated to afford numerous flame passages 51, but the top 52 thereof is preferably formed of an imperforate slab. The walls of the auxiliary combustion chamber may be 35 assumed to be built up of fire brick, and the top 52 thereof may be assumed to be of similar baked fire-clay substance, but in any event, the walls and top of this auxiliary fire box should be of highly refractory material.

40 The operation of this latter form of burner will be very similar to the operation of the first described form of burner. That is to say, when the mechanism is initially set into operation, combustion will be first established in the auxiliary combustion chamber 28a and the flame thus produced will be blown into the combustion chamber 40 through the pilot fire flue 29a, thereby establishing combustion of the cold fuel and air mixture projected into the combustion 45 chamber 40 through the tortuous generating passages or ducts 25a. Part of the flame produced in and issuing from the combustion chamber 40 will be intercepted by the baffle 42 and discharged as an annular flame which will completely surround the intermediate portion of the burner head 21a. This rearwardly diverted annular flame will rapidly heat up the generating 50 passages 25a, and when these are hot, the cold fuel mixture will be heated beyond its critical 55 point and vaporized before delivery to the combustion chamber 40.

60 The major portion of the flame produced in the combustion chamber 40 will be discharged from the combustion chamber 40 through the axial 65 opening 44 in the baffle 42 into the auxiliary fire box 49. After a short period of operation the walls and top of the auxiliary fire box 49 will become heated to a very high temperature, which will be a further assurance of complete combustion. The flame introduced into the auxiliary fire box 49 will issue from the numerous side wall openings 50 thereof, and the hot fumes will pass upwardly in close relation to the heat transfer walls 53 of the boiler 45.

As previously indicated it is important in carrying out the invention that the nozzle 20 be of the type which breaks the fuel up into very small particles, and in this connection it may be stated that the invention has been successfully practised with the use of commercially obtainable nozzles used in connection with high pressure gun type burners such, for example, as are manufactured by the Bird Oil Company of Minneapolis, Minnesota, the Hubbard Oil Company of Minneapolis, Minnesota, the Sigwald Engineering Corporation of Minneapolis, Minnesota, and the Campbell Machine Company of Minneapolis, Minnesota, and numerous others.

Nozzles of this character are obtainable in various volumetric capacities ranging from a gallon and a half per hour under approximately one hundred pounds of pressure to three gallons an hour upwardly under approximately one hundred pounds of pressure. Another source of such nozzles is Nitroil Laboratories, St. Paul, Minnesota. Since the nozzles described deliver their rated fuel output at approximately one hundred pounds pressure, it may be assumed for the purposes of this case that the fuel pumps 16 and 16a are capable of delivering fuel to their respective nozzles 20 or 20a under approximately one hundred pounds pressure.

What I claim is:

1. In a hydrocarbon burner adapted to burn non-volatile hydrocarbon fuels, a mixing chamber, a pair of generating tubes opening from the mixing chamber in diverging relation and arranged to discharge toward substantially the same point, means for maintaining forced circulation of air through said mixing chamber and generating tubes, means for introducing such a fine spray of non-volatile hydrocarbon fuel into the mixing chamber that it will mix with the air moving through the mixing chamber and generating tubes to produce a cold but highly inflammable mixture, the discharge ends of the generating tubes being so arranged with respect to the intermediate portions of the generating tubes that the heat of combustion of the mixture discharged from the generating tubes will heat the intermediate portions of the generating tubes.

2. The structure defined in claim 1 in which the said generating tubes discharge into a common combustion chamber, that is so arranged with respect to the intermediate portions of the

generating tubes that flames will issue therefrom to heat the generating tubes.

3. The structure defined in claim 1 in which the said generating tubes discharge into a common vertically disposed combustion chamber having an open upper end above the discharge ends of the generating tubes and apertures below the generating tubes for omission of flames for heating the generating tubes.

4. The structure defined in claim 1 in which the said generating tubes open into a common horizontally disposed combustion chamber that is located entirely beyond the generating tubes, and in further combination with means for intercepting flame issuing from the horizontally disposed combustion chamber and diverting the same backwardly about the generating tubes.

5. The structure defined in claim 1 in further combination with an automatic ignition system comprising an auxiliary mixing chamber laterally spaced from but closely associated with the aforesaid mixing chamber, a fire flue opening from the auxiliary mixing chamber and having its discharge end closely associated with the discharge ends of said generating tubes, the other end of said mixing chamber being subject to said forced air-circulation means, means for diverting a portion of sprayed fuel mixture moving in the first said mixing chamber and delivering the same to the said auxiliary mixing chamber, and means for igniting the mixture in said auxiliary mixing chamber.

6. The structure defined in claim 1 in further combination with an automatic ignition system comprising an auxiliary mixing chamber laterally spaced from but closely associated with the aforesaid mixing chamber, a fire flue opening from the auxiliary mixing chamber and having its discharge end closely associated with the discharge ends of said generating tubes, the other end of said mixing chamber being subject to said forced air-circulation means, means for diverting a portion of the sprayed fuel mixture moving in the first said mixing chamber and delivering the same to the said auxiliary mixing chamber, and electrical means for igniting the mixture in said auxiliary mixing chamber, said electrical ignition means including spaced arcing electrodes located within the auxiliary combustion chamber.

GEORGE PIRICH.

50
